Primary Examiner — Zenia I Bennett

(74) Attorney, Agent, or Firm — Dilworth & Barrese, LLP

(57) **CLAIM**

The ornamental design for neck hair grooming guide, as shown and described.

DESCRIPTION

FIG. 1 is a front view of the neck hair grooming guide showing my new design;

FIG. 2 is a back view of the neck hair grooming guide showing my new design;

FIG. 3 is a top view of the neck hair grooming guide showing my new design;

FIG. 4 is a bottom view of the neck hair grooming guide showing my new design;

FIG. 5 is a left side view of the neck hair grooming guide showing my new design;

FIG. 6 is a right side view of the neck hair grooming guide showing my new design;

FIG. 7 is a perspective view of the neck hair grooming guide showing my new design;

FIG. 8 is a rear view of the neck hair grooming guide showing my new design; and,

FIG. 9 is a rear view of the neck hair grooming guide showing my new design.

The broken lines illustrate the environment of the neck hair grooming guide and form no part of the claimed design.

1 Claim, 4 Drawing Sheets
